(57) **CLAIM**

The ornamental design for the tire pressure gauge, as shown and described.

DESCRIPTION

FIG. 1 is an upper front perspective view of a tire pressure gauge in accordance with the present invention;

FIG. 2 is an upper rear perspective view thereof;

FIG. 3 is a lower front perspective view thereof;

FIG. 4 is a lower rear perspective view thereof;

FIG. 5 is a front elevation thereof;

FIG. 6 is a rear elevation thereof;

FIG. 7 is a side elevation thereof;

FIG. 8 is an opposite side elevation thereof;

FIG. 9 is a top plan view thereof; and,

FIG. 10 is a bottom plan view thereof.

The dashed lines in FIGS. 1–10 represent pressure fittings for the tire pressure gauge of the present invention and form no part of the claimed design.
